UNITED STATES PATENT OFFICE.

WILLIAM A. WILLIAMS, OF NEW ROCHELLE, NEW YORK, ASSIGNOR OF ONE-HALF TO
JOSEPH V. CARROLL, OF NEW ROCHELLE, NEW YORK.

GUTTER-HANGER.

966,632.

Specification of Letters Patent.

Patented Aug. 9, 1910.

Application filed October 5, 1908, Serial No. 456,307. Renewed January 24, 1910. Serial No. 539,869.

To all whom it may concern:

Be it known that I, WILLIAM A. WILLIAMS, a citizen of the United States, residing at New Rochelle, in the county of Westchester 5 and State of New York, have invented a new and useful Improvement in Gutter-Hangers, of which the following is a specification.

This invention relates to gutter hangers, the object being to provide a gutter hanger 10 which can be easily and quickly attached to the roof of a building and one which will adjust itself to suit any size gutter.

Another object of my invention is to provide a hanger which can be easily and 15 quickly adjusted so as to give the gutter the proper drain and one which is so constructed that after being adjusted there is no danger of it becoming loose.

A further object of my invention is to 20 provide a hanger which is exceedingly cheap and simple in construction and one which is composed of a very few parts which are so arranged and connected together that it is almost impossible for the parts to become 25 loose when in use.

With these various objects in view, my invention consists in the novel features of construction and arrangement of parts herein-after described and claimed.

30 In the drawings forming a part of this specification:—Figure 1 is a side elevation of my improved gutter hanger showing the application of the same to a roof, the gutter being shown in section. Fig. 2 is a section 35 taken on line 2—2 of Fig. 1. Fig. 3 is a section taken on line 3—3 of Fig. 1. Fig. 4 is a plan view of the fastening pin. Fig. 5 is a top plan view of the locking sleeve.

In carrying out my improved invention I 40 employ an angled bracket A adapted to be secured to the roof of a building by any suitable means the depending vertical portion of which is provided with a series of openings A'. The depending portion extends through 45 a slot formed in the U-shaped portion C of a strip B, and is provided with oppositely disposed openings through which a fastening pin D is adapted to extend which is provided with an angled portion D' adapted to 50 fit around the U-shaped portion, when resting on the strip B so as to securely lock the pin in place so that all danger of it becoming loose is prevented and it will be seen that when it is desired to remove the pin it is 55 swung upwardly against the edge of the de-

pending portion of the bracket so as to throw the angled portion D' out of engagement with the U-shaped portion which will allow the pin to be drawn out of the opening so that the strip can be adjusted on the bracket. 60

The strip B is provided with an angled end B' to which is secured the angled end E' of a substantially semi-circular strap E by a rivet or any other suitable means the other end of the strap E being provided with a 65 substantially open ring shaped loop E² the extreme end of which is bent inwardly as shown at E³ adapted to rest on the other end of the strip B which is provided with an angled end B² which forms a stop and prevents the strap from drawing apart. The end E³ is secured on the strap B by a sleeve F which will securely lock the strap in position and is held thereon by frictional contact with the strap E. It will be seen that 70 by this arrangement the strap can be easily and quickly placed around the gutter G the loop portion fitting snugly around the beading of the gutter and it will be seen that the loop portion of the strap will give so 75 as to fit snugly around different styles of gutters.

From the foregoing description it will be seen that I have provided a gutter hanger which is so constructed that it can be easily 80 and quickly attached to a gutter or detached therefrom and one which can be adjusted on the supporting bracket so as to give the gutter the proper drain. 85

What I claim is:—

1. A gutter hanger comprising a supporting bracket provided with a series of openings, a strip provided with a slotted U-shaped portion and having oppositely disposed openings adjustably mounted on said bracket, a pin adapted to extend through the openings of the strap and bracket provided with an angled portion adapted to fit around the U-shaped portion of the strap, a substantially semi-circular strap carried by 95 said strip, said strap being provided with an open ring shaped portion adjacent one end and means for securing the free end of said strap to said strip. 100

2. A gutter hanger comprising an angled bracket provided with a series of openings, a strip provided with a U-shaped portion having a slot and provided with oppositely disposed openings adjustably mounted on the bracket, a pin adapted to extend through 105 110 the bracket, a pin adapted to extend through 115

said openings of the U-shaped portion and bracket, said pin being provided with an angled portion adapted to fit around the U-shaped portion of the strip locking the same within the openings of the strip and bracket and a strap carried by said strip together with means for securing the free end of said strap to said strip.

3. A gutter hanger comprising an angled bracket adapted to be secured to the roof of a building provided with a series of openings in its vertical portion, a strap provided with a central upwardly projecting U-shaped portion having a slot to receive said vertical portion of the bracket and provided with

oppositely disposed openings adapted to register with the openings of the bracket, a pin adapted to be forced through said openings provided with an angled portion adapted to fit around the U-shaped portion of said strip, a strap secured to one end of said strip provided with an open ring portion adjacent its free end, said strip being provided with an angled end and a sleeve surrounding said strip and strap for securing said strap thereon.

WILLIAM A. WILLIAMS.
